(57) **CLAIM**

The ornamental design for a substrate processing system carrier, as substantially shown and described.

DESCRIPTION

FIG. 1 shows a top perspective view of a substrate processing system carrier in accordance with the present invention; FIG. 2 shows a bottom perspective view thereof; FIG. 3 shows a top plan view thereof; FIG. 4 shows a bottom plan view thereof; FIG. 5 shows a left side elevation view thereof; FIG. 6 shows a right side elevation view thereof; FIG. 7 shows a front elevation view thereof; FIG. 8 shows a rear elevation view thereof; FIG. 9 shows a top perspective view thereof in its intended environment; and, FIG. 10 shows a top perspective view thereof in its intended environment. The broken lines in the drawings illustrate environment that forms no part of the claimed design.
